No. 805,206.

PATENTED NOV. 21, 1905.

W. H. JORDAN.
HAND OPERATED PUMP.
APPLICATION FILED MAR. 29, 1905.

FIG 1

UNITED STATES PATENT OFFICE.

WILLIAM H. JORDAN, OF HAYS, KANSAS.

HAND-OPERATED PUMP.

No. 805,206.

Specification of Letters Patent.

Patented Nov. 21, 1905.

Application filed March 29, 1905. Serial No. 252,681.

To all whom it may concern:

Be it known that I, WILLIAM H. JORDAN, a citizen of the United States, and a resident of Hays, in the county of Ellis and State of Kansas, have invented a new and Improved Hand-Operated Pump, of which the following is a full, clear, and exact description.

The object of the invention is to provide novel features of construction for a hand-operated pump which adapt it for very convenient and effective service as an instrument for the abstraction of pus or extravasated blood from a wound, boil, or ulcer on the human body.

The invention consists in the novel construction and combination of parts, as is hereinafter described, and defined in the appended claims.

Reference is to be had to the accompanying drawings, forming a part of this specification, in which similar characters of reference indicate corresponding parts in the views shown.

Figure 1 is a sectional side view of the pump, taken substantially on the line 1 1 in Fig. 2; and Fig. 2 is a transverse sectional view substantially on the line 2 2 in Fig. 1.

The pump cylinder or barrel 5, of tubular form, is afforded a suitable length and diameter for convenient use and effective service, one end being furnished with a closing-cap 5^a. Upon the opposite end of the pump-barrel 5 is mounted a valve-case 6, the latter having a rounded periphery and a central bore *a*, that is diametrically enlarged at and near one end and internally threaded therein for a screwed engagement with the threaded end of the pump-barrel. The contour of the valve-case 6 is preferably bulbous, and on the end opposite from that wherein the barrel 5 is screwed a nipple 6^a is centrally formed. The bore *a* at a proper distance from the adjacent end of the barrel 5 terminates in a flat wall *a'* and thence is extended as a passage *a'* of reduced diameter through the projected nipple 6^a.

An end wall *b* is formed or secured upon the extremity of the pump-barrel 5, that occupies the threaded portion of the bore *a*, and this wall is centrally perforated, as shown at *b'*.

A circular valve-block 7 is formed on one end of a longitudinally-fluted stem 7^a, the stem being loosely inserted in the passage *a'*, the valve-block being slidable in the bore *a*, the latter constituting a valve-chamber.

Between the valve-block 7 and the end wall *b* a coiled spring 8 is placed, the expansion of which normally holds the valve-block seated on the flat wall *a'*, which serves as a valve-seat.

A passage *c* extends laterally from the valve-chamber *a* and from the outer end thereof is counterbored to produce a valve-chamber *c'*, wherein a check-valve 9 is held to reciprocate by the loose insertion of a fluted stem 9^a thereon into the passage *c*. The check-valve 9 is pressed by a spring 10, so as to hold it normally engaged with its seat, closing the passage *c*, and, as shown, said spring has contact at one end with an axially-perforated plug 11, that is screwed into the valve-chamber *c'*.

A piston consisting of two gum or leather cups 12, held between two washers 12^a, is mounted and secured upon one end of a piston-rod 13. The piston fits neatly in the tubular barrel 5, and the rod 13 projects through a central perforation in the cap 5^a, a handle 13^a of any preferred form being secured on the outer end of the said rod to adapt it for reciprocation manually.

Upon the nipple 6^a one end portion of a suction-cup 14 is mounted. Said cup, which is preferably formed of soft rubber, may have the free end turned laterally, as shown at 14^a, and flared near the edge, thus adapting this open end to be conveniently applied over the inflamed protuberance that a boil or carbuncle generally assumes.

It is to be understood that for general service of the character specified several different forms of the suction-cup may be provided and exchanged to enable a proper engagement of the same with a boil, ulcer, or wound, the location of the latter determining the most available shape and trend of the nozzle end of the cup from the tubulate body of the same.

A passage *d* of small diameter is formed in the valve-case 6, extending from the passage *a'* through the periphery of the case, and in a recess *d'*, that is formed in the exterior of the case around the outer end of the passage *d*, a sealing-valve *d*^a is pivoted, the valve normally seating over the passage. On the valve *d*^a a handle *d*^b is formed or secured, that projects laterally therefrom, and, as shown in Fig. 1, the relative arrangement of the valve adapts a depression of the free end of the handle *d*^b to raise the valve and open the passage *d*.

- In use it will be seen that the open end of the suction-cup 14 is to be placed over a boil or the like and held in position. The handle 13^a is now drawn slowly outward, which will draw the air forward in the interior of the pump-barrel 5 and unseat the valve 7, a return stroke of the piston in the barrel 5 closing the valve 7 and opening the check-valve 9, thus effecting a discharge of air from the pump-barrel and valve-chamber *a*. The second outward movement of the handle 13^a repeats the exhausting action just described and produces a partial vacuum in the suction-cup 14, which will cause a flow of pus from the diseased tissue into the valve-chamber *a*, the inward movement of the plunger now closing the valve 7 and opening the check-valve 9, simultaneously effecting a discharge of the pus from the check-valve chamber *c* in an obvious manner. When the liquid discharge from the inflamed tumor has been withdrawn, the suction-cup 14 may be released for easy removal by applying pressure upon the lever-handle *d*³, so as to raise the valve *d*² and admit air to the suction-cup, thus equalizing air-pressure on the outer and inner surfaces of said cup, which will of course release it from enforced engagement with the tumor.
- It will be noted that the improved pump may be constructed in very compact form, so as to be small and light. Furthermore, its novel construction adapts the instrument for general application to different parts of a person and permits its effective use for withdrawal of diseased blood from an ulcer or a surcharge of milk from the nipple of a diseased breast.
- Having described my invention, I claim as new and desire to secure by Letters Patent—
1. In a hand-pump, the combination with a barrel having a centrally-perforated end

wall, a centrally-perforated removable cap on the other end of the barrel, a double-cup piston, a piston-rod thereon working respectively in the barrel and through the cap, and a handle on the outer end of the piston-rod, of a bulbous-shaped valve-case having a central valve-chamber in one end, receiving the end of the barrel having the perforated end wall, an axially-perforated nipple extended from the opposite end of the valve-case, the passage through the nipple intersecting the valve-chamber, a spring-pressed valve having a fluted stem, the valve and its stem respectively working in the valve-chamber and passage in the nipple, a check-valve controlling a lateral passage leading from the valve-chamber out of the valve-case, and an elastic suction-cup mounted at one end on the nipple.

2. A suction and force pump, embodying a cylindrical barrel, a double-cupped piston, a rod extended from the piston and working through a cap on one end of the barrel, a valve-case on the other end of the barrel, a nipple formed centrally on the case and having a perforation longitudinally therethrough, a valve in the case controlling the passage in the nipple, a lateral passage from the valve-case, a valve controlling said passage, the nipple having a lateral passage extended therefrom for induction of air thereinto, a relief-valve controlling said air-passage and manually operative from the exterior of the case, and a suction-cup mounted at one end on an end of the nipple.

In testimony whereof I have signed my name to this specification in the presence of two subscribing witnesses.

WILLIAM H. JORDAN.
